UNITED STATES PATENT OFFICE.

WILLIAM H. AVERILL, OF BOSTON, MASSACHUSETTS, ASSIGNOR TO OWL SUPPLY COMPANY, OF BOSTON, MASSACHUSETTS, A CORPORATION OF MASSACHUSETTS.

NOTE-BOOK.

1,184,296.

Specification of Letters Patent.

Patented May 23, 1916.

Application filed July 29, 1915. Serial No. 42,525.

To all whom it may concern:

Be it known that I, WILLIAM H. AVERILL, a citizen of the United States, and resident of Boston, Dorchester district, in the county of Suffolk and State of Massachusetts, have invented certain new and useful Improvements in Note-Books, of which the following is a specification.

This invention relates to note books such as those used by stenographers, and it has for its object to provide a note book having a confining attachment of simple construction securely engaged with one of the covers of the book, without undesirably increasing the thickness of said cover, said attachment being adapted either to hold the book in the form of a self-supporting easel standing upright on a desk, or to confine an exposed leaf and other leaves below it when the book lies flat on the desk.

The invention consists in the improvements which I will now proceed to describe and claim.

Of the accompanying drawings forming a part of this specification: Figure 1 represents a perspective view of a note book embodying my invention and adjusted to stand upright on a desk; Fig. 2 represents a perspective view showing the book lying flat; Fig. 3 represents a side view of one of the covers without the attachment; Fig. 4 represents a view similar to Fig. 3, showing the attachment engaged with the cover; Fig. 5 represents a section on line 5—5 of Fig. 4; Fig. 6 represents a perspective view of the attachment; Fig. 7 represents a side view of a portion of the back cover of the book and a modified form of attachment embodying the invention; Fig. 8 represents a section on line 8—8 of Fig. 7.

The same reference characters indicate the same or similar parts in all the views.

In the drawings, referring first to Figs. 1 to 6 inclusive, 12 represents the stiff back cover of a note book, said cover being provided with transverse alined slots 13 in its opposite longitudinal edges. To the cover 12 are applied two U-shaped clips 14, each composed of a strip of thin sheet metal bent to form two ears bearing on opposite sides of the cover and a neck connecting said ears and bearing on a longitudinal edge of the cover at opposite sides of a slot 13 therein. In other words, the clips 14 bestride the slotted portions of the cover and conceal the

slots. The neck portions of the clips are provided with orifices 15 coinciding with the slots 13. The edges of the slots and the clips constitute hinge socket members of which the walls of the orifices 15 form parts. 60 The attachment also includes a bail bent from a length of wire to form oppositely projecting hinge pintles 17 inserted in the orifices 15 and slots 13, and therefore adapted to turn in said socket members, a transverse portion 18 adapted to extend across the book, and arm portions 19 connecting the portion 18 with the pintles 17. 65

The sheet metal pieces forming the clips 14 are first bent to the L-shaped form shown 70 by full lines in Fig. 6. The pintles 17 are then inserted in the orifices 15, and confined therein by the resilience of the bail. The cover 12 is then laid upon the inner ears of the clips to cause its slots to receive the 75 pintles 17, and the other ears of the clips are bent inwardly against the cover, as indicated by dotted lines in Fig. 6. The attachment is thus securely engaged with the cover, the engagement of the pintles with the 80 edges of the slots preventing the bail and clips from moving lengthwise of the cover, and the resilience of the bail confining the pintles and clips against movement crosswise of the cover. 85

The bail may be adjusted to enable the book to stand upright like an easel, one leg of which is formed by the back cover 12 and the other by the cover 12^a, as shown by Fig. 1. The bail may also be used as shown by 90 Fig. 2 to confine leaves of the book against the back cover 12 when the book is opened and lies flat.

It will be seen that the thickness of the cover 12 is increased only by the thickness 95 of the thin sheet metal ears of the clips, the pintles 17 being located in the body of the cover without projecting from the sides thereof, as shown by Fig. 5.

Figs. 7 and 8 represent a modification 100 omitting the slots 13 and showing a clip 14^b bestriding the edge of a back cover 12^b and having spurs 14^b penetrating said cover, a bail arm 19^a, and a short pintle 17^a inserted in an orifice 15^a in the neck of the clip 105 14^b and held therein by the resilience of the bail. In this embodiment of the invention the spurs 14^b prevent displacement of the clips and bail from their operative positions relatively to the cover. 110

Having described my invention, I claim:

1. A note book having hinge sockets on one of its covers, a confining bail composed of a length of wire bent to form oppositely projecting hinge pintles engaged with said sockets, a transverse portion adapted to extend across the book, and arm portions connecting said transverse portion with said pintles, the pintles being held in engagement with the sockets by the resilience of the bail.
- 5 2. A note book having U-shaped clips bestriding its longitudinal edges and provided with pintle-receiving orifices, and a confining bail having pintles journaled in said orifices, a transverse portion adapted to extend across the book, and arms connecting the transverse portion with the pintles, means being provided for preventing displacement of the bail and clips from their operative relation to the cover.
- 10 3. A note book having U-shaped clips bestriding its longitudinal edges and provided with pintle-receiving orifices, and a confining bail having pintles journaled in said

orifices, a transverse portion adapted to 25 extend across the book, and arms connecting the transverse portion with the pintles, means being provided for preventing displacement of the bail and clips from their operative relation to the cover, the pintles 30 being held in engagement with the clips by the resilience of the bail.

4. A note book having alined transverse slots in one of its covers, U-shaped clips bestriding the slotted portions of said cover 35 and having orifices in their neck portions alined with said slots, said clips and slots constituting hinge sockets, and a leaf-confining bail composed of a length of wire bent to form oppositely projecting hinge pintles 40 engaged with said sockets, a transverse portion adapted to extend across the back, and arm portions connecting said transverse portion with said pintles.

In testimony whereof I have affixed my 45 signature.

WILLIAM H. AVERILL.
